UNITED STATES PATENT OFFICE.

LAWRENCE RADFORD, OF WASHINGTON, DISTRICT OF COLUMBIA.

FIRE CONTROL.

Application filed March 28, 1920, Serial No. 368,157. Renewed March 19, 1926.

To all whom it may concern:

Be it known that I, LAWRENCE RADFORD, a citizen of the United States, residing at Washington, District of Columbia, have invented new and useful Improvements in Fire Control, of which the following is a specification.

This invention relates to improvements in fire control and more particularly to the method and apparatus of controlling the fire of guns on battleships although it is, of course, to be understood that without material modifications certain features are applicable to the control of guns in other locations or to the control of other instruments such as searchlights on battleships or other places.

One of the objects of the present invention is to provide an improved apparatus for fire control of simple and practical construction which will be reliable and efficient in operation.

A further object is to provide an apparatus of the above character in which the errors in operation will be reduced to a minimum.

A further object is to provide an improved method of fire control whereby greater accuracy in gun fire is obtained.

It is believed that these and other objects will perhaps be more clear to those skilled in the art by the following brief statement of the problem involved and the means whereby the same is solved.

For purposes of illustration, reference is made to the accompanying sheets of drawing wherein Figures 1, 2 and 3 are diagrammatic views intended to show the angles existing between the line of sight and the line of bore and the trunnional line of the guns together with the variations produced in these angles.

Figures 4 and 5 which will hereinafter be referred to more in detail are intended to show in vertical sections at right angles to each other the construction of the apparatus involved.

With these figures in mind it may be stated that the present invention has for its purpose the elimination of certain errors in the control of the fire of the guns, the nature of which errors may be more readily explained by reference to Figures 1, 2 and 3.

In Figure 1, let GG represent the axis of the bore of a gun which may be elevated or depressed about its transverse trunnions, the

axis of which trunnions is denoted by T. Let the line SS represent the axis of the sighting instrument attached to said gun. Let it be assumed, as is most commonly the case in the design of gun sights, that the sighting instrument whose axis is denoted by SS is capable of a certain amount of elevation or depression in its bearings, and that the axis of said bearings is parallel to axis TT. In making ready to fire the gun at a target whose distance is such that the trajectory of the projectile must needs be curved, the sighting instrument is first depressed in its bearings so that its axis, SS, makes a certain predetermined angle with the axis of the bore of the gun, said angle being that which is known to be necessary in order that the projectile will travel the desired distance when the line of sight, SS, has been directed toward the target. Let this angle be denoted by α . The line of sight, SS, is then directed toward the target by elevating the gun about axis TT and turning the whole carriage in which said gun is mounted about a vertical axis. It is well known in the science of gunnery that errors in the aim of such a gun will be introduced unless the line of sight, SS, and the axis of the bore of the gun, GG, lie in the same vertical plane, or in parallel vertical planes not far separated. Figures 2 and 3 are diagrams by means of which said errors may be explained. In Figure 2 the line of sight, SS, and the axis of the bore of the gun, GG, are shown as lying in the same vertical plane. This condition can exist, under the assumption already made, only when the axis of the trunnions of the gun, TT, lies in the horizontal plane HH. Now let it be assumed that the axis TT no longer lies in the horizontal plane HH, but is inclined from said plane, as shown in Figure 3, wherein the line T'T' denotes the inclined position of the axis of the trunnions. Let it be assumed that this inclination, the amount of which may be denoted by ν , is such that line T'T' lies in a vertical plane perpendicular to the line SS. It is obvious, from consideration of Figure 3, that, under such conditions, the vertical plane of the trajectory of the projectile fired from the gun whose axis is denoted by GG, will not pass through the target, since it is assumed that line SS is directed toward the target.

Let the angle between the vertical plane through GG, and the vertical plane through

SS be denoted by M. It can be shown that the value of M is such that,

$$\tan M = \tan e \sin r.$$

5 Moreover, it will also be found, when the conditions illustrated in Figure 3 exist, that the projectile will not travel a sufficient distance. This error is due to the fact that the angle of elevation of GG above the horizontal plane HH, which angle may be denoted by N is such that,

$$\sin N = \sin e \cos r.$$

18 From this equation it follows that N is always less than e, and the error in elevation of GG, which may be denoted by P, is such that,

$$P = e - \sin^{-1} (\sin e \cos r).$$

20 These two errors, viz M and P, may be eliminated provided the sighting device of the gun is so designed and constructed that the line of sight and the bore of the gun always lie in the same vertical plane, or in 25 parallel vertical planes not far separated and further provided that the design and construction of said sighting device is such that the vertical angle between the bore of the gun and the line of sight is maintained 30 constant for a given setting or adjustment of the sighting device for range. The device, the construction and method of operation of which are hereinafter described, serves to fulfill these conditions for the elimination of 35 the errors M and P to a very high degree of precision.

Figure 4 shows a longitudinal vertical section of one embodiment of the invention, and,

40 Figure 5 is an end view of the same. 1 is a case mounted in bearings 2, 2 in the lugs 3, 3 cast in one with plate 4. This permits rotation of the case 1 about the axis AA. The plate 4 carries another pair of lugs 5, 5 by which it is supported in the frame 6 on 45 bearings 7, 7, being capable of rotation about the axis BB through a certain angle. In Figures 4 and 5 the device is shown mounted on a gun director, or directorscope, which, 50 as is well known, is an instrument used, particularly in naval gunnery, for the purpose of controlling the fire of a gun, or group of guns, from a point removed from said gun or guns. In this embodiment of 55 the invention, the frame 6 is supported by bearings 8, 8 on the standards 9, 9, which are attached rigidly to the plate 10 of the directorscope. This plate 10 is capable of being trained in azimuth about the axis CC.

60 11 is a sector of a circular rack, struck from a point on BB as a center, immovably attached to the plate 4, and having engraved on one of its flat surfaces a scale showing the angle through which plate 4, together 65 with the case 1, must be depressed about the

axis BB to correspond to a given range of the gun or guns whose fire is to be controlled by the directorscope. This depression is accomplished by means of the pinion 12, which is secured to shaft 13 carrying handwheel 14.

The frame 6 carries a sector of a worm wheel 15, with which the worm 16 meshes. This worm is driven by shaft 17, which in turn is driven by the handwheel 18 through 75 bevel gears (not shown).

19 and 20 are the horizontal and vertical parts, respectively, of a periscope, the eyepiece being at 21, part 19 being coaxial with axis AA. The line of sight from the objective of this periscope in part 20 is perpendicular to axis AA and is reflected through an angle of approximately 90° by a mirror 22. The horizontal part of the periscope 19, is securely attached to the case 1, 80 while the vertical part, 20, is capable of a certain amount of rotation about its own axis in the bearing 23 in the case 1.

There is attached immovably to the case 1, a periscope, 24, by means of the bracket 25. The eyepiece of this periscope, coaxial with the bearings 2, 2 and the upper end of the periscope is provided with a prism, 27, by means of which the line of sight is directed at right angles to the plane determined by the optical axes of the horizontal and vertical portions of the periscope denoted by 19 and 20. 28 is a sector of a worm wheel with its center on the line AA, cut on piece 29, which is immovably secured to the case, 1. This worm wheel meshes with a worm on a shaft 30, which shaft is carried in bearings in the plate 4, and is provided with a crank, 31, at each end.

Piece 32 is provided with a collar 33 which is locked securely to the tube of the periscope 20, and at its lower end is provided with a journal, 34, coaxial with bearings 23, into which journal fits a pin or shaft, 35, securely attached to the case, 1. The horizontal arm of piece 32 carries, in a bearing at its end, a fork 36, which fork is rotatable in its bearing about its own longitudinal axis. Frame 6 carries a bracket 37, to which is immovably attached a standard, 38, to 110 which is fixed a pin 39. This pin 39 fits between the two prongs of the fork 36, and is so located that it is coaxial with the bearings 2, when the scale on the circular rack 11 reads zero.

Plate 4 carries a standard, 40, to which is immovably attached a pinion 41, said pinion being concentric with axis AA. A pinion 42 of the same number of teeth as 41 is keyed non-rotatably to a shaft 43, supported in a bearing in piece 44, said piece 44 being immovably attached to case 1. Pinion 45, which has two-thirds as many teeth as 41 and 42, is also keyed to shaft 43, and meshes with a pinion 46, which has one and one- 120

third as many teeth as pinions 41 and 42, or twice as many as pinion 45. This pinion 46 is keyed to a shaft 47, which is carried in two bearings in piece 44, and whose axis coincides with axis AA. The shaft 47 is not continuous, the two parts thereof being securely attached to a member 48. In member 48 is cut a sector of a circular groove, with the center of the circle on the axis of the vertical periscope tube 20. The bottom of this groove is a flat surface lying a short distance below axis AA.

A pin 49 is carried in a bearing 50 in piece 32, said pin being capable of lengthwise motion, but not of rotation, in its bearing. This pin 49 carries at its lower end a small roller 51, the radius of said roller being equal to the minimum distance between axis AA and the flat bottom surface of the groove in piece 48. Said pin 49 is also provided with a flange 52 whereby a compression spring 53, the other end of which presses against part 50, keeps the roller 51 in contact with the bottom surface of the groove in piece 48. At its upper end the pin 49 is attached to one arm of a bell crank 54, by means of a pin 55. This bell crank 54 is carried on bearings 56 on lugs on the collar 33, one lug and bearing being located on each side of the periscope tube 20, the upper arm of the crank 54, being forked at its inner or bearing end, and the lower arm of said bell crank being attached to one prong of the fork of the upper arm, said lower arm hanging alongside of the vertical portion of the periscope. The upper arm of said bell crank is provided with a telescopic joint 57, in order to allow for small variations in length. The length of pin 49 is such that, when its axis lies in the plane determined by the horizontal and vertical axes of the periscope, 19, 20, the upper arm of the bell-crank, 54, will be perpendicular to the axis of 20.

The lower end of the lower arm of the bell-crank 54, carries a small roller 58. The mirror 22 is capable of rotation through a small angle in bearings 59 in the headpiece of the periscope, the axis of said bearings being parallel to the axis of the bearings 56. The roller 58 is so located that the distance from its axis to the axis of the bearings 56 is equal to the distance between the axis of bearings 56 and the axis of bearings 59. A lever 60 is non-movably attached to the frame carrying the mirror 22, and is, therefore, capable of a certain degree of rotation about the axis of bearings 59. A smooth bearing surface is machined on one face of the lever 60 at its lower end, the plane of which bearing surface would, if continued, pass through the axis of 59. A coiled spring 61 is attached at one end to a pin on the lower arm of the bell-crank 54, and at the other end to a pin on lever 60. This spring

serves to keep the roller 58 constantly in contact with the aforesaid machined surface on lever 60. A level 62 is so attached immovably to bracket 25 that it will register when the plane determined by the axes of parts 19 and 20 is vertical.

E denotes the point of intersection of pin 39 with the longitudinal axis of the fork 36, and O denotes the point of intersection of axes AA and BB.

In case the invention were embodied in a gun director, or directorscope, as shown in Figures 4 and 5, and hereinbefore described, suitable means would also be provided to transmit to the personnel manning the gun or guns, whose fire it is desired to control, information concerning the azimuth angle to which the device is trained about its axis CC, and also the angle through which the frame 6 is elevated or depressed about the axis of its bearings in the lugs 9, 9. This information may be transmitted to the gun personnel either automatically, by means of suitable mechanical or electrical transmitters and receivers, or by means of telephones, voice tubes, or other means of non-automatic transmission. Said means of communication are not shown in the present specification, since their design and use is well known, and, furthermore, since the present invention relates more particularly to the means by which the sighting mechanism is supported and controlled.

If it is assumed that the gun or guns whose fire it is desired to control are so mounted that the axes around which they may be trained are parallel, or substantially so, to the axis CC, and that the trunnions of said guns are perpendicular, or substantially so, to the axes about which the guns are trained, it is obvious that the screws of said guns, by proper elevation and training thereof, may cause said guns to partake of all the motions of the frame 6.

The method of operation of the invention hereinbefore described is as follows:

The whole instrument is first turned about the axis CC until the image of the target lies on the vertical cross-line of the periscope 19. In order to bring the target within the field of view of the periscope, it may be necessary to elevate or depress the periscope by operating the handwheel 18, which is so located that it is conveniently operated by the person observing through the periscope. Let it be assumed, for the moment, that when the directorscope is so trained that the image of the target falls on the vertical cross-line of the periscope, the axis of the bearings in which frame 6 is carried, and consequently axis BB, are horizontal. Let it also be assumed, momentarily, that case 1 stands upright in its bearings 2, 2, i. e., that the axis of part 20 lies in a vertical plane passing through the target. Plate 4, case 1, and con-

sequently the periscope 19-20 are now depressed about axis BB, by means of the hand-wheel 14, through an angle denoted by e , corresponding to the range, or distance to the target, said angle being set by reference to the scale engraved on part 11, said scale moving past an index or reference mark on frame 6. Since the standard 38, and pin 39, are immovably fixed with respect to frame 6, it is obvious that, as the case 1, and the periscope 19-20, are depressed about axis BB, the fork 36 will slide downward past the pin 39, and, as a result, a line passing through points O and E will make with axis AA an angle equal to the angle e . The frame 6, and consequently the whole sight device are now elevated about the bearings in the lugs 9, 9, until the image of the target falls on the horizontal as well as on the vertical cross-line of the periscope. The angle of elevation which it may be necessary to apply to the sighting mechanism by means of hand-wheel 18 may or may not be equal to the angle e . In other words, axis CC of the directorscope may or may not be perpendicular to a line drawn from the directorscope to the target.

In the preceding paragraph it has been assumed that conditions were such that the axis BB is horizontal. Now let it be assumed that such a condition no longer obtains but that the axis BB is inclined in a plane at right angles to a line from the directorscope to the target. If such inclination exists, the transverse trunnions of the guns whose fire is to be controlled will also have the same, or substantially the same, inclination, since it has been assumed that the directorscope is so mounted that its axis CC is parallel to, or substantially parallel to, the axes about which the guns are trained. When such inclination of axis BB occurs, it is the function of the cross-leveler to maintain case 1, and consequently the periscope 20, in a vertical plane passing through the target, by proper manipulation of the cranks 31. For this purpose he may observe the horizon at a point 90° from the line of sight to the target, by means of the periscope 24, or he may determine when the periscope 19-20, lies in said vertical plane by means of the level 62. When the cross leveler operates the cranks 31 he thereby turns the case 1 in its bearings 2, 2, about axis AA. But since the axis of pin 39 no longer coincides with axis AA, it is obvious that, as case 1 is rotated about AA, the pin 39 will press against one or the other of the prongs of fork 36, and thus cause rotation of piece 32, and of part 20 of the periscope about the axis of the bearings 23 and 34. Now it has been shown how, given proper means of communication between the directorscope and the gun or guns whose fire it is desired to control, the bore of said gun or guns may be caused to

partake of all the motions of frame 6, either in elevation or depression, or in train, and, therefore, that the bore of said gun or guns may always be maintained parallel to a line passing through points O and E, since both points are fixed with relation to frame 6. It is, therefore, obvious that, by means of the mechanisms and operations hereinbefore described, the line of sight of the periscope 19-20, and the bore of the gun or guns with which communication is established, may be maintained in the same vertical plane or in parallel vertical planes not far separated. In order that this vertical plane, or these vertical planes, shall also pass through the target, it is only necessary that the whole sighting mechanism be turned about axis CC until the image of the target again falls on the vertical cross-line of the periscope, and that the gun or guns be trained through the same angle.

As has been pointed out, the pinion 41 is immovably fixed to the standard 40, and therefore to plate 4. Therefore, as case 1 is caused to rotate in its bearings 2, 2, through any given angle, pinion 42 will thereby be caused to rotate about its own axis through an equal angle, and by means of pinions 45 and 46, the grooved piece 48 will be caused to rotate about axis AA through half the angle through which the case 1, is rotated in its bearings 2, 2. Moreover the arrangement of these pinions and parts is such that the rotations of part 48, and case 1, each about axis AA, is always in the same direction. However, said rotation of the case 1, causes rotation of piece 32 about the axis of bearings 23 and 34, as has already been pointed out. This rotation of piece 32 causes the pin 49 to move laterally in such manner as to describe a sector of a cylindrical surface, said cylindrical surface being coaxial with bearings 23 and 34. Let it be assumed that axis BB is so inclined, in a plane perpendicular to a line from the directorscope to the target, that the left end of said axis BB, as seen from the position of the directorscope operator looking into eyepiece 21, is lower than the right hand end, and that said axis BB makes an angle in said plane with the horizontal denoted by r . Obviously this angle r is the angle through which the cross-leveler must rotate the case 1, in order that part 20 shall lie in a vertical plane passing through the target. By so doing, said cross-leveler causes part 32 to rotate about its axis through an angle M , such that,

$$\tan M = \tan e \sin r.$$

Moreover the direction of this rotation of part 32 is in a direction toward the end of axis BB which is depressed, or to the left, according to the assumption already made. But since piece 48, and therefore the flat bottom surface of the circular groove cut there-

in, is also inclined in the same direction, but through half the angle, as axis BB, it is obvious that the pin 49 will have imparted to it, by the action of the spring 53, a downward motion on its bearing 50. This downward motion of pin 49 will impart to the piece 54 an angular motion about the axis of bearings 56. The amount of said angular motion of piece 54 about the axis of bearings 56, which angular motion may be denoted by Q, is such that,

$$\tan Q = \sin M \tan 1/2 r.$$

It is also obvious that the arrangement of piece 54, particularly the lower arm thereof, lever 59, roller 58, and the axes of bearings 56, 59 and the bearing of roller 58, as hereinbefore described, is such that lever 60, and, therefore, mirror 22, are caused to rotate about the axis of bearings 59 through an angle equal to $1/2 Q$ and also that the motion of mirror 22 about its axis is in the same direction as the motion of part 54 about the axis of bearings 56. Therefore, according to the well known laws of reflection, the line of sight of the periscope is deflected, by said rotation of the mirror 22, through the angle Q and said deflection of the line of sight is in the same direction as the rotation of part 54 about the axis of bearings 56.

It has been pointed out hereinbefore that the gun or guns whose fire is to be controlled by the directorscope may be caused to partake of all the motions of the frame 6. Such being the case, the bore of said guns may be caused to remain parallel to line OE, since points O and E are both fixed with respect to the frame 6. Also, it is obvious that, by means of the mechanisms and operations described above, the line of sight of the periscope and the line OE may be caused to lie in the same vertical plane, and that the angle between said two lines may be maintained constantly equal to

$$\sin^{-1} (\sin e \cos r) + \tan^{-1} (\sin M \tan 1/2 r).$$

Furthermore, calculation of the value of this expression for various values of e and r will show that it is very nearly equal to the value of e, even though the values assigned to e and r may each be as large as 30 degrees, the discrepancy in said values being so minute as to be negligible.

It should be noted that all the operations performed by means of handwheels 14 and 18 and cranks 31, and the training of the directorscope as a whole, may be performed at once, if so desired, without the performance of any one of said operations interfering seriously with the performance of any other one. Also it should be noted that either handwheels 14 or 18, or both, may be operated when axis BB is horizontal or inclined, or when case 1 stands vertical or

is inclined, or when any combination of said conditions exists.

From the above it is believed that the construction method of use and operation will be clear to those skilled in the art. The invention embodies a relatively simple construction which is believed to accomplish, among others, all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and, therefore, such adaptations should and are intended to be comprehended within the meaning and range of equivalency of the following claims.

What I claim is:—

1. In an apparatus for controlling the fire of one or more guns, said apparatus consisting in part of a sighting unit, of a support for said sighting unit rotatable about an axis approximately parallel to a line to the target, of means for maintaining said support in an approximately constant relation to a horizontal line perpendicular to a line from the sight to the target, and of suitable means of communication whereby each of said gun or guns may be kept trained to the same bearing as the sighting unit, suitable mechanisms whereby such maintenance of said support in said relation to said horizontal line automatically causes lateral deviation of the line of sight of said sighting unit through the same angle, and in the same direction, as the lateral deviation of the vertical plane containing the axis of bore of each of said gun or guns caused by the inclination of the trunnions thereof.

2. In an apparatus for controlling the fire of one or more guns, said apparatus consisting in part of a sighting unit, of a support for said sighting unit rotatable about an axis approximately parallel to a line from the sight to the target, of means for maintaining said support in approximately parallel to a line from the sight to the target, of means for maintaining said support in approximately constant relation to a horizontal line perpendicular to a line to the target, and of suitable means whereby each of said gun or guns may be kept trained to the same bearing as the sighting unit, suitable mechanisms whereby such maintenance of said support in said relation to said horizontal line automatically causes depression of the line of sight of said sighting unit equal to the loss in elevation of each of said gun or guns due to the inclination of the trunnions thereof.

3. In an apparatus for controlling the fire

- of one or more guns, consisting in part of a sighting unit containing at least two reflecting members, of a member rotatable about an axis approximately parallel to a line to the target, of means for maintaining said rotatable member in an approximately constant relation to a horizontal line perpendicular to a line to the target, and of suitable means for keeping each of said gun or guns trained to the same bearing as said sighting unit, suitable mechanisms whereby such maintenance of said rotatable member of the sighting unit in constant relation to said horizontal line causes rotation of one of the said reflecting members about a substantially vertical axis, with respect to the other reflecting member, through an angle very nearly equal to the lateral deviation of the plane of fire of each of said gun or guns due to the inclination of the trunnion thereof.
4. In a sighting apparatus comprising, in part, means whereby the apparatus may be set for a desired angle, and means whereby one member of said apparatus may be rotated about its axis in such manner as to keep its position in space fixed when the apparatus as a whole is inclined about an axis approximately parallel to a line to the object sighted, suitable mechanisms whereby the operation of keeping said member fixed in space automatically causes deviation of the line of sight of said apparatus about two mutually perpendicular axes, each such deviation being equal to the change in magnitude of the corresponding component of the angle for which the apparatus is set caused by the aforesaid inclination of said apparatus.
5. In a sighting apparatus consisting, in part, of means whereby said apparatus may be adjusted for an arbitrarily chosen angle, or a member rotatable about an axis approximately parallel to a tenet from the sight to the object sighted, and of means whereby said rotatable member may be maintained in a fixed relation to a horizontal line perpendicular to a line to the object sighted, suitable means whereby such maintenance of said rotatable member in fixed relation to said horizontal line perpendicular to a line to the object sighted automatically makes compensation for the change in value of the horizontal and vertical components of said arbitrarily chosen angle due to the inclination of said apparatus.
6. In a sighting apparatus containing at least one reflecting member, and consisting in part of a member rotatable about an axis approximately parallel to a line from the sight to the object sighted, of means of adjustment for an arbitrarily chosen angle and of means for maintaining said rotatable member in a fixed position with relation to a horizontal line perpendicular to a line to the object sighted, suitable mechanisms whereby such maintenance of said rotatable member in said fixed position with relation to said horizontal line automatically turns said reflecting member through an angle substantially equal to one-half the product of the sine of the arbitrarily chosen angle with the cosine of the angle through which the sighting unit is included about an axis parallel to a line to the object sighted.
7. In an apparatus for the control of the fire of a gun or guns consisting in part of a sighting unit, of a member rotatable about an axis approximately parallel to a line to the target, of means for maintaining said rotatable member in a fixed position relative to a horizontal line perpendicular to a line to the target, of a support for said sighting unit, and of suitable means whereby the axis of bore of said gun and guns may be maintained in a fixed relation to said support both in elevation and train, suitable mechanisms whereby such maintenance of said rotatable member in a fixed relation to said horizontal line automatically compensates for the change in elevation of said gun due to inclination of the trunnions thereof, by suitable deviation of the line of sight of said sighting instrument.
8. In an apparatus for the control of the fire of a group of guns, consisting of a sighting unit, of means for maintaining the support of said sighting unit in an approximately constant relation to the vertical, and of suitable means of communication between the support of said sighting unit and each of said guns, suitable means whereby the error in train of each of said guns due to the inclination of the trunnions thereof may be compensated for by reason of the mechanisms embodied in said sighting unit and the support thereof.
9. In an apparatus for the control of the fire of a group of guns, consisting of a sighting unit, of means for maintaining the support of said sighting unit in an approximately constant relation to the vertical, and of suitable means of communication between the support of said sighting unit and each of said guns, suitable means whereby the error in elevation of each of said guns due to the inclination of the trunnions thereof may be compensated for by reason of the mechanisms embodied in said sighting unit and the support thereof.

Signed at Washington, District of Columbia, this 9th day of January, 1920.

LAWRENCE RADFORD.
